Primary Examiner — Thomas Johannes(74) Attorney, Agent, or Firm — Advent; Ryan T. GraceCLAIM

The ornamental design for a packaging assembly, as shown and described.

DESCRIPTION

FIG. 1 is a perspective view of a packaging assembly showing our new design;

FIG. 2 is a front elevation view thereof;

FIG. 3 is a back elevation view thereof;

FIG. 4 is a first side elevation view thereof;

FIG. 5 is a second side elevation view thereof;

FIG. 6 is a top plan view thereof; and,

FIG. 7 is a bottom plan view thereof.

Portions of FIGS. 1 and 4-7 are shown in dashed lines to depict unclaimed subject matter and form no part of the claimed design.
